Atty.

UNITED STATES PATENT OFFICE.

ASA FRED BATCHELDER, OF SCHENECTADY, NEW YORK, ASSIGNOR TO THE GENERAL ELECTRIC COMPANY, OF NEW YORK.

SPACE-BLOCK FOR ARMATURE-CORES.

SPECIFICATION forming part of Letters Patent No. 595,364, dated December 14, 1897.

Application filed September 15, 1897. Serial No. 651,731. (No model.)

To all whom it may concern:

Be it known that I, ASA FRED BATCHELDER, a citizen of the United States, residing at Schenectady, in the county of Schenectady, State of New York, have invented certain new and useful Improvements in Space-Blocks, (Case No. 619,) of which the following is a specification.

This invention relates to space-blocks of dynamo-electric machines in which the armature-core is built up in the usual manner with annular iron laminæ in layers suitably supported upon an internal support or spider adapted for the purpose.

The invention has for its object to provide a light, strong, stiff, and durable space-block constructed and arranged as hereinafter set forth and claimed.

In the accompanying drawings, Figure 1 is a view in perspective, showing portions of three space-blocks, that at the left being a portion of a space-block constructed in accordance with this invention and those at the right being modifications. Fig. 2 is a detailed plan view showing a space-block located between two bundles of laminæ, and Fig. 3 is a detail view of the outer edge of a lamina adapted for this invention.

In carrying out this invention the space-block is constructed with an internal support or spider 1, having its arms 2 provided with a circumferential flat strip of metal or ring 3, mounted on and secured thereto in any suitable manner. Mounted on and secured to the strip or ring 3 are radial arms or branches 4, consisting of thin strips of metal, as shown at the left of Fig. 1.

A space-block constructed as hereinbefore set forth is located between two bundles of laminæ.

If desired, in order to prevent the thin radial strips or arms on the periphery of the strip or ring 3 from being bent and displaced, the radial strips may be secured in any suitable manner to the adjacent laminæ of the two bundles of laminæ between which the space-block is located. This may be accomplished, for example, by one of the modifications shown at the right of Fig. 1, in which the radial arms 5 consist of thin strips of metal formed with lateral projections 6 ad-

jacent to their outer ends, which engage slots 7 in the arms 8 of the laminæ 9 adjacent to the space-block located between two bundles of laminæ 10, as shown in Fig. 2. By means 55 of this construction the radial strips or arms 5 are held rigidly in place and kept from bending. In either form of the invention a light, strong, and durable construction is provided. In the other modification at the right 60 of Fig. 1 the space-block is provided with arms 11, consisting of thin strips of metal formed with a single lateral projection 12 adjacent to their outer ends. In this case the outer ends of the arms 11 engage but one lamina 10 by 65 means of projections 12 engaging slots 7.

This invention is shown as employed in a toothed armature, the arms 8 of the laminæ 9 forming the projecting armature-teeth. The radial arms of the space-block correspond in 70 number to and are in alinement with the projecting armature-teeth. By this means ventilating-spaces are afforded.

I claim—

1. A space-block for armature-cores, consisting of an internal support or spider, a circumferential ring mounted on the arms of the spider, and radial arms consisting of thin strips of metal mounted on said circumferential ring, as set forth. 75

2. A space-block for armature-cores, consisting of an internal support or spider, a circumferential ring mounted on the arms of the spider, and radial arms consisting of thin strips of metal mounted on said circumferential ring and having lateral projections adjacent to their outer ends, as set forth. 85

3. In an armature-core, the combination with sections of built-up laminæ, of a space-block consisting of an internal support or 90 spider, a circumferential ring mounted on the arms of the spider, and radial arms consisting of thin strips of metal mounted on said circumferential ring, the space-block being located between two sections of built-up 95 laminæ, and the radial arms being secured at their outer ends to the said sections.

4. In an armature-core, the combination with sections of built-up laminæ, of a space-block located between two sections of built-up laminæ, the laminæ adjacent to the space-block being provided with slots, and the 100

space-block consisting of an internal support or spider, a circumferential ring mounted on the arms of the spider, and radial arms consisting of thin strips of metal mounted on the circumferential ring and having lateral projections adjacent to their outer ends, engaging the slots in the laminæ adjacent to the space-block, as set forth.

5. A space-block for armature-cores, consisting of an internal support or spider, a flat ring mounted on the arms of the spider, and radial arms consisting of thin metallic strips mounted on the flat ring, as set forth.

6. In an armature-core, the combination with sections of built-up laminæ having radial arms forming a toothed structure, of a space-block consisting of an internal support or spider, a circumferential ring mounted on the arms of the spider, and radial arms consisting of thin strips of metal mounted on said circumferential ring, the space-block being located between two sections of built-up

laminæ, and its radial arms corresponding in number to and in alinement with the radial arms of the built-up laminæ, as set forth. 25

7. In an armature-core, the combination with sections of built-up laminæ having radial arms forming a toothed structure, of a space-block consisting of an internal support or spider, a circumferential ring mounted on the arms of the spider, and radial arms consisting of thin strips of metal mounted on said circumferential ring, the space-block being located between two sections of built-up laminæ and its radial arms corresponding in 30 number to and secured to and in alinement with the radial arms of the built-up laminæ, as set forth.

In witness whereof I have hereunto set my hand this 13th day of September, 1897.

ASA FRED BATCHELDER.
